SPARK PLUG

Charles R. Boyd, Chicago, Ill.

Application September 12, 1934, Serial No. 743,669
Renewed March 5, 1937

4 Claims. (Cl. 123—169)

This invention relates to improvements in spark plugs for internal combustion engines.

It is an object of my invention to provide a spark plug which is self-cleaning in use, which will fire longer without becoming fouled with oil, which will maintain a fixed spark gap, which will generally have a longer life and which may be readily assembled and disassembled.

It is further an object of my invention to provide a spark plug in which the ground electrode is positioned diametrically of the plug and will act to split and deflect the oil to prevent clogging and fouling of the spark gap by the oil.

It is a still further object of my invention to provide a spark plug having venting openings disposed laterally with respect to the spark gap, which will permit escape of the oil deflected by the ground electrode and prevent fouling and short-circuiting of the plug.

In this connection, 20 a more specific object is to provide vent openings of a shape and so arranged as to form a relatively thin ring of metal at the base of the plug which will heat up readily and burn off any oil that may be deposited on the ring or on the ground electrode having association with said ring.

A further object resides in the provision of a spark plug having a center electrode protected by refractory material to substantially its lower end, thus exposing only the tip of the electrode which 30 also readily heats up during use and burns off any oil or other matter deposited thereon.

Further objects and advantages of my improvements will be more readily apparent from the following description taken in connection with 35 the attached drawing, in which

Figure 1 is a side elevation of my improved plug and showing in section a portion of the cylinder wall in which the spark plug is mounted.

Figure 2 is a side elevation of the spark plug, 40 the view being taken at right angles to that of Figure 1;

Figure 3 is a vertical section taken on the plane indicated 3—3 in Figure 2;

Figure 4 is a plan view of the lower end of the 45 plug;

Figure 5 is a side elevation of a modified form of the plug, and

Figure 6 is a plan view of the bottom end of the plug shown in Figure 5.

The spark plug in the usual manner includes a 50 metallic shell 10 having a threaded portion 12 whereby the plug may be threaded into the cylinder wall 14, as illustrated in Figure 1. The head of the shell 10 is formed with a nut portion 16 for threading the plug into the wall 14 and a

gasket 18 may be used for sealing the joint between the shell 10 and the wall 14.

The shell 10 is tubular in form and is adapted to receive an insulator 20, which is intended to be of the best grade of refractory and having a 5 conical tip 22 which extends within the shell into the engine cylinder. The insulator is sealed to the shell 10 by gaskets 24 positioned beneath the shouldered portion 26 of the insulator and is detachably secured in position by the sleeve nut 10 28, which threads into the shell 10 and engages an additional gasket 30 above the shouldered portion 26 of the insulator. An electrode 32 extends axially through the insulator 20 and the outer extremity 34 of the electrode is provided with a 15 terminal connector 36. The inner extremity 38 of the electrode 32 protrudes for a short distance beyond the tip 22 of the insulator.

I provide a ground electrode 40 positioned diametrically with respect to the shell 10 and fixedly 20 secured at its ends to the shell 10. It will be apparent that since the electrode 40 is rigidly secured in position, that it is not subject to deflection by the heat and therefore the spark gap between the ground electrode 40 and the central 25 electrode 38 remains substantially fixed. By my arrangement the spark gap is disposed substantially axially of the plug instead of at one side of the central electrode and therefore there is no tendency for the central electrode to burn 30 unevenly. Furthermore, by my arrangement the oil in the engine cylinder which may be forced into the plug is deflected by the electrode 40 and prevented from fouling the spark gap.

I provide novel means for venting the spark 35 plug. Thus, in the construction of Figures 1 to 4, I show notched outwardly flaring openings 42 cut into the sides of the shell 10. It will be noted that the notches as shown are cut in such manner that the lower cut is approximately horizontal 40 while the upper cut is at an angle thereto, thereby leaving a thin ring-shaped portion 44 of the shell 10 surrounding the electrode 40. The ring-shaped portion 44 provides a flat protecting end for the plug so that the plug may be handled and set 45 down on a support without danger of breaking the porcelain insulator. The notched openings cover a considerable area and thereby enable free venting of the flame and oil from the plug and prevent fouling of the plug. By my arrangement, 50 if it is necessary to clean the plug, the parts may be readily disassembled and cleaned and when again assembled it is not necessary to adjust the spark gap since the electrodes, when assembled, will be in proper relative position.

The lateral openings 42 provide vent openings for the spark gap and also form a ring-shaped portion 44. This relatively thin metal ring may also be formed by a plurality of openings such as shown in Figure 5 to be presently described, wherein the ring is supported from the body of the shell by several narrow portions. The ring readily heats up during use of the plug and therefore burns off any oil or other matter deposited thereon. The ground electrode associated with the ring portion is also maintained at a relatively high temperature and thus is self-cleaning. This self-cleaning feature is also present in the center electrode which is covered and protected by the insulator 22 except for the lower tip 38. This tip therefore readily heats up and likewise burns off the oil that may be deposited thereon.

Although I have shown in Figures 1 to 4 a preferred design of my plug, it will be obvious that other forms may be resorted to without departing from the spirit of my invention and the venting openings may be formed in different manners. For example, I have shown one modified construction in Figures 5 and 6 in which the spark plug construction is substantially as that disclosed in Figures 1 to 4 except that the shell 10, instead of being formed with notched openings, is provided with a plurality of radial holes 58. In both forms it will be apparent that the venting openings are laterally disposed with respect to the spark gap and it should also be noted that the lower or inner end of the insulator 22 terminates in a horizontal plane with or preferably above the inner and upper edges of the venting openings in order to prevent fouling of the insulator and burning of the electrode. It has been found by test that spark plugs as disclosed herein will have a longer life without failure than other plugs now on the market when used under similar conditions and it is believed that the improvements in operation are due to the novel arrangement and cooperation between the ground electrode and the venting openings.

Various changes and modifications may be resorted to in the practice of my invention without departing from the spirit of my invention as expressed in the appended claims.

I claim:

1. A spark plug comprising a metallic shell adapted to be threaded into a cylinder wall, a ground electrode diametrically positioned with respect to said shell and fixedly secured at its ends to the lower end of said shell, an insulating electrode-retaining body positioned centrally within said shell and removably secured thereto to provide an axial spark gap, said shell having notched openings formed therein adjacent the lower end thereof and above said ground electrode, said notched openings being so formed as to leave a

substantially thin ring-shaped portion at the lower end of said shell and said openings being laterally disposed with respect to the axial spark gap between the electrodes.

2. A spark plug comprising a substantially tubular metallic shell adapted to be threaded into a cylinder wall, a notched vent opening formed in the lower end of said shell below the threaded portion thereof by a substantially horizontal cut and an angular cut, a ground electrode diametrically positioned with respect to the lower end of said shell and fixedly secured to said shell immediately beneath said notched opening, an insulator centrally positioned within said shell and removably secured thereto, the lower end of said insulator terminating substantially adjacent the upper edge of said notched opening and an electrode carried by said insulator and axially projecting from the lower end thereof to provide an axial spark gap with respect to said ground electrode, whereby said vent opening is laterally disposed with respect to said spark gap.

3. A spark plug comprising a substantially tubular metallic shell having an external thread thereon whereby said shell may be threaded into a cylinder wall, the lower end of said shell beneath said external thread having a pair of notched openings cut therein through a large area thereof and defining at the lower end of said shell a substantially thin ring-like portion supported from the body of said shell by relatively narrow uncut portions, a ground electrode diametrically positioned with respect to said ring-like portion and fixedly secured at its ends thereto, an insulator centrally positioned with respect to said shell and removably secured thereto, a central electrode carried by said insulator and projecting from the lower end thereof to leave a substantially axial spark gap between said electrodes whereby oil is deflected from said spark gap by said ground electrode and vented through said opening to prevent fouling of the plug.

4. A spark plug comprising a metallic shell, an insulator centrally positioned within said shell, an electrode fixedly secured to the lower end of said shell, an axially disposed electrode carried by said insulator and projecting from the lower end adjacent to said ground electrode to leave a spark gap, said shell having a plurality of notched openings formed therein above said ground electrode and disposed substantially laterally with respect to the spark gap, said notched openings having a size and being arranged so as to leave a substantially thin ring-shaped portion at the lower end of said shell, whereby said relatively thin ring portion will heat up readily and burn off any oil that may be deposited on the ring or on the ground electrode having association therewith.

CHARLES R. BOYD.
